UNITED STATES PATENT OFFICE.

FRANCOIS JOSEPH DE SPOTURNO COTY, OF PARIS, FRANCE.

DESIGN FOR A BOTTLE.

Application filed June 14, 1922. Serial No. 2,680. Term of patent 14 years.

To all whom it may concern:

Be it known that I, FRANCOIS JOSEPH DE SPOTURNO COTY, a citizen of the Republic of France, residing in the city of Paris, France, have invented a new, original, and ornamental Design for a Bottle, of which the following is a specification, reference being had to the accompanying drawing, forming a part thereof.

In the drawing,

I claim:

The ornamental design for a bottle substantially as shown.

FRANCOIS JOSEPH de SPOTURNO COTY.
